(57) CLAIM

The ornamental design for a toe portion of a shoe, as shown and described.

DESCRIPTION

FIG. 1 is a perspective view of a toe portion of a shoe showing our new design;

FIG. 2 is a left side view thereof;

FIG. 3 is a right side view thereof; and,

FIG. 4 is a top view thereof.

The dash-dot-dash lines immediately adjacent the shaded areas represent the bounds of the claimed design while all other broken lines are directed to environment and are for illustrative purposes only; the broken lines form no part of the claimed design.

1 Claim, 4 Drawing Sheets
